V. S. McDONOUGH

FENCE WIRE FASTENING

Filed April 30, 1926

Victor S. McDonough INVENTOR

BY Victor J. Evans

WITNESS J. D. Wright

ATTORNEY

UNITED STATES PATENT OFFICE.

VICTOR S. McDONOUGH, OF CAMDEN, OHIO.

FENCE-WIRE FASTENING.

Application filed April 30, 1926. Serial No. 105,826.

This invention relates to fastenings for use upon fences which, owing to the construction thereof may be readily and easily applied upon the posts and which may not be come disengaged from the post upon the deterioration of the latter.

With the above and other objects in view, the invention further includes the following novel features and details of construction, 10 to be hereinafter more fully described, illustrated in the accompanying drawing and pointed out in the appended claim.

In the drawing:

Figure 1 is a perspective of a fence-post 15 with the present invention applied and used in conjunction therewith;

Figure 2 is a sectional view through a cross sectioned T-shaped post with the invention applied;

Figure 3 is a fragmentary side elevation thereof;

Figure 4 is a fragmentary perspective of the upper end of an angle post with the invention applied;

Figure 5 is a transverse section taken through a cross sectioned angular post with the invention applied;

Figure 6 is a fragmentary side elevation of the invention as applied upon an angular post.

Referring to the drawing in detail wherein like characters of reference denote corresponding parts, the reference characters 10 and 11 indicate the usual and conventional forms of cross sectioned substantially T-shaped and angular shaped posts respectively; the post 10 having obliquely and oppositely and horizontally disposed openings 12 provided in the face thereof and extending upon the opposite sides of the center portion thereof, while the post 11 has correspondingly disposed openings 13 arranged in the offset portion thereof substantially as illustrated in Figures 2 and 5 of the drawing respectively.

Such openings 12 are formed in pairs at appropriate distances upon the lengths of the respective posts in order that staples such as indicated at 14 may be driven within the openings 12, which owing to their oppositely disposed relationship will converge outwardly in reverse order, whereby the wire 15 whether straight or barbed will be firmly held in place upon the face of the posts against accidental displacement. 50

It is to be noted that the staples 14 when driven, in the manner as previously described and illustrated, will firmly hold the wire 15 in place and taut upon the post, and which may not become disengaged therefrom due to any deterioration of the posts, owing to the fact that the posts as previously described and illustrated are formed of metal. The pointed or pronged ends of the staples 14 may be struck to disengage the 65 same from the posts in the instance of taking down the fence. 55

The invention is susceptible of various changes in its form, proportions and minor details of construction, and the right is herein reserved to make such changes as properly fall within the scope of the appended claim. 70

Having thus described my invention what I desire to claim as new is:— 75

As a new article of manufacture, a metallic fence post having pairs of oppositely and horizontally disposed openings entering the post in alignment and formed obliquely therethrough at spaced intervals along the 80 length thereof, and staples having their respective arms fitted and driven within the openings which cause the arms to diverge outwardly in opposed directions for retaining lengths of wire upon the post. 85

In testimony whereof I affix my signature.

VICTOR S. McDONOUGH.
